John C. Penne.

UNITED STATES PATENT OFFICE.

JACOB C. GOSE, OF REELSVILLE, ASSIGNOR OF ONE-HALF TO RICHARD H. BOWEN, OF PUTNAMVILLE, INDIANA.

MOTOR.

SPECIFICATION forming part of Letters Patent No. 388,858, dated September 4, 1888.

Application filed October 31, 1887. Serial No. 253,876. (No model.)

To all whom it may concern:

Be it known that I, JACOB C. GOSE, a citizen of the United States, residing at Reelsville, in the State of Indiana, have invented certain new and useful Improvements in Motors; and I do hereby declare the following to be a full, clear, and exact description of the invention, such as will enable others skilled in the art to which it appertains to make and use the same.

10 This invention relates to motors actuated by hand and foot power; and it consists in the improved contrivance hereinafter described, whereby a simple and efficient construction is presented that will be suitable for driving road vehicles, light machinery, &c.

In the accompanying drawings, forming part of the specification, Figure 1 is a side elevation of a motor embodying my improvements, and Fig. 2 is a plan view of the same.

20 The supporting-frame of the machine consists of a base-piece and end sections, A B. The end sections, A and B, are connected and braced together at their upper ends, respectively, by cross-bars *a* and *a'*. The section A consists of two standards, each of which comprises two parallel beams, *b* and *c*, while the section B comprises but two standards, *d* and *e*.

25 *C* represents longitudinally-inclined bars, secured at one end to the standards and having their front portions extending beyond the sections A. The front portions of said bars *C* are slotted, as shown at *c'*, for the purpose hereinafter explained.

30 *D* represents a cross-bar connecting the forward ends of the bars *C*.

A top bar, *E*, connects the front and rear sections, and, as represented, is curved to carry a seat, *f*, for the operator.

35 Bearing in the standards *d e* is a shaft, *F*, the projecting ends of which are bent to form oppositely-extending cranks *g g*, each carrying a horizontal wrist-pin, *h*, at its outer end. A gear-wheel, *G*, between the standards *d e*, is mounted to rotate with the shaft *F* and mesh 40 with a pinion, *i*, above on a shaft, *H*, journaled in a bearing, *j*, located upon the upper side and near the rear end of one of the side bars *C*. A wheel, *I*, is located on the end of said shaft *H*, which may be a sprocket or belt 45 wheel to transmit power.

Although actuating-levers are located on both sides of the machine, they differ only in relative positions to accord with the oppositely-extending cranks *g*, so that it will only therefore be necessary to describe the construction and arrangement of one side in order to understand both.

55 An extended pitman, *J*, is connected to the crank *g*, and extends forwardly between the beams *b c*, where it is connected pivotally to the lower bifurcated end of a vertical arm, *L*, the upper end of which is pivotally connected by a horizontal link, *l*, with the lower end of a hand-lever, *L*, hung on the cross bar *a* between the beams *b c*.

60 An extended bracket-strip, *M*, is secured on the outer side of each beam *c*, and is curved outward, as shown in Fig. 2, to form a vertical guide space between it and the side of the beam *c*. A pin, *m*, receives the bracket and enters the beam to form a pivot, upon which is mounted a lever, *N*, having a bent inner end, *o*, to form a pedal for the operator's foot, while its outer end is pivotally connected by a link, *P*, with the forward end of a beam, *O*, centrally pivoted in the side bar *C*, and pivotally connected by a link, *q*, with the wrist-pin *h* of the crank *g*.

65 As will be seen, the forward portion of the beam *O* plays in the space between the bracket-strips *M* and adjacent beam.

70 The operation of the machine will be readily understood. The operator occupies the seat *f*, so as to alternately depress the pedals and vibrate the levers *L L*, which results in the pitmen *J* and beams *O*, actuating the cranks *g*, to rapidly and easily rotate the gear-wheel *G*, so as to rapidly drive the pinion *I* and its belt-wheel. The construction of the actuating devices is such that a comparatively slight exertion will, by reason of the larger leverage, rapidly rotate the gear-wheel and its pinion.

75 I claim—

80 1. The combination, with the supporting-frame, of the drive-shaft provided with oppositely-extending cranks and with links *q*, pivoted to the outer ends of said cranks, the oppositely-extending hand-levers, the pitman-bars connected to the cranks and to the levers, and foot-levers having foot-connections with 85

centrally-pivoted beams, said beams being pivoted to links q , substantially as described.

2. The combination, with the supporting-frame having the front and rear sections, the former consisting of standards formed of pairs of beams, of the drive-shaft having the oppositely-extending cranks, the oppositely-extending hand and foot levers, pitman-bars guided between said standard-beams, and a centrally-

pivoted beam having its front portion guided to by a bracket-strip and link-connections, substantially as shown and described.

In testimony whereof I affix my signature in presence of two witnesses.

JACOB C. GOSE.

Witnesses:

MARY G. WEBB,
ELIZABETH STOOPS.
